DRIVING DEVICE

Loy O. Allen, Athens, Pa., assignor to Ingersoll-Rand Company, New York, N. Y., a corporation of New Jersey

Application May 6, 1942, Serial No. 441,986

2 Claims. (Cl. 1—46.1)

This invention relates to driving devices, and more particularly to a driving device adapted for attachment to a pneumatically actuated hammer tool for driving railroad spikes and similar articles.

One object of the invention is to protect a non-striking part of the driving device against damage or breakage.

A more specific object is to prevent complete compression of the spring serving to hold the spike guiding element of the driving device in the guiding position.

Other objects will be in part obvious and in part pointed out hereinafter.

In the drawing accompanying this specification and in which similar reference numerals refer to similar parts,

Figure 1 is an elevation, partly in section, of the driving device showing it applied to the front end of a hammer tool,

Figure 2 is a transverse view taken through Figure 1 on the line 2—2, and

Figure 3 is a view similar to Figure 1 illustrating the manner in which the spring element of the driving device is protected from injury by the driving member whenever the driving device assumes a position in which the guiding element or sleeve member of the guiding device is fully retracted upon the driving member.

Referring more particularly to the drawing, the driving device, designated in general by 20, is in many respects similar to that disclosed in United States Patent No. 2,272,760 granted to me February 10, 1942. It, accordingly, comprises a driving member 21 having a sleeve member or guide 22 slidable thereon for maintaining the driving device in driving relation with a spike 23 intended to be driven into a tie 24 for securing a rail 25 thereto.

The shank 26 of the driving member 21 extends into the end of a percussive tool casing 27 to receive the blows of a hammer piston 28 and the driving device is normally maintained in the correct relation with respect to the hammer piston by a retainer spring 29 having a coil, or coils, at one end in interlocking engagement with the periphery of the casing 27. The forward end of the spring interlockingly engages a shoulder 30 on the driving member to prevent ejection of said driving member from the casing.

As in the structure shown in the aforesaid patent, the stem 31 of the driving member 21 carries a collar 32 intermediate its ends and the peripheral surface 33 of said collar is in slidable engagement with the wall of the bore 34 in the

sleeve 22. Likewise, the portion of the stem 31 lying forwardly of the collar 32 extends slidably through a reduced portion 35 of the bore in the front end of the sleeve to assist in guiding the sleeve upon the driving member.

A spring 36 is, moreover, disposed about the stem 31 forwardly of the collar 32 to seat at one end against the collar and at its other end against a shoulder 37 in the bore for holding the sleeve 22 normally in a forwardly position on the driving member so that a part of the reduced portion 35 of the bore will lie forwardly of the stem 31 to receive the head of the spike 23 for holding the driving device in substantially the correct driving relation with the head of the spike. This forward limiting position of the sleeve upon the stem 31 is determined by a spring-ring 38 arranged in the rearward end of the bore 34 to engage the corresponding end of the collar 32 for retaining the sleeve upon the stem.

A difficulty frequently experienced during the driving of a spike with a power-driven hammer tool is that of maintaining the driving member in driving position upon the spike when the spike head approaches the rail flange. Under these circumstances, the sleeve element of the driving device will also engage the rail flange and during the subsequent driving of the spike the stem 31 moves through the sleeve so that frequently little or no engagement exists between the wall of the sleeve and the spike head.

By reason of the rapidity at which the hammer tool operates the entire device is subjected to such severe vibration that the striking end of the stem often slides off of the spike head, say to the position illustrated in Figure 3 of the drawing, so that the end of the sleeve may rest upon the spike. Any blows thereafter delivered to the driving member may have the effect, in certain cases, to impel the driving member forwardly in the sleeve with such force as to crush the spring between its seats on the sleeve and the driving member.

It is accordingly contemplated herein to prevent the application of damaging blows to the spring within the sleeve, and to this end the bore 34 of the sleeve is provided with an intermediate portion 39 of smaller diameter than the portion of the bore containing the collar 32 to normally serve as a receptacle for the forward coils of the spring 36. A shoulder 40 is thereby provided at the rearward end of the portion 39 of the bore to serve as an abutment for the collar 32 for limiting the distance which the sleeve 22 may move rearwardly upon the stem 31.

The intermediate portion 39 of the bore is of somewhat greater length than the length of the spring when fully compressed so that when the collar 32 engages the shoulder 40 suitable clearances will exist between the coils of the spring 36 to preclude the chances of driving them into contact with each other. Thus, in the event that during the driving of a spike the driving device assumes a position in which the sleeve is caused to move to its rearmost limiting position with respect to the stem 31 the force thereafter delivered to the driving member will be transmitted to the sleeve instead of to the spring, and the latter will, therefore, be fully protected against injury.

I claim:

1. A driving device for use with a percussive tool having a casing and a reciprocatory hammer therein, comprising a driving member extending into the casing to receive the blows of the hammer, a sleeve member slideable on the driving member to maintain the driving member in driving relation with an element intended to be driven, a shoulder on the driving member, a shoulder on the sleeve member, a compression spring in the sleeve member to seat against the shoulders for holding the sleeve member in a limiting position upon the driving member, and an abutment

on one of said members for the shoulder on the other said member to limit slideable movement of the sleeve member in one direction on the driving member and thereby prevent the forcing of the coils of the spring against each other.

2. A driving device for use with a percussive tool having a casing and a reciprocatory hammer therein, comprising a driving member extending into the casing to receive the blows of the hammer, a sleeve member slideable on the driving member to maintain the driving member in driving relation with an element intended to be driven, the bore in said sleeve consisting of a plurality of portions of different diameters, a shoulder on the driving member to cooperate with the bottom of the portion of maximum diameter of the bore for limiting movement of the sleeve in a rearwardly direction upon the driving member, and a compression spring in an intermediate portion of the bore to seat against the shoulder for moving the sleeve in a forwardly direction upon the driving member and being of shorter length when fully compressed than the length of such intermediate portion of the bore to prevent the forcing of the coils of the spring against each other.

ROY O. ALLEN.
